UNITED STATES PATENT OFFICE.

ALBERT J. NYSTROM, OF WHEATON, ILLINOIS.

MAP-HOLDER.

No. 886,723.

Specification of Letters Patent.

Patented May 5, 1908.

Application filed July 5, 1907. Serial No. 382,164.

To all whom it may concern:

Be it known that I, ALBERT J. NYSTROM, a citizen of the United States, residing at the city of Wheaton, in the county of DuPage and State of Illinois, have invented a new and useful Improvement in Map-Holders, of which the following is a specification.

My invention relates to devices for housing and preserving maps or charts, and by which 10 they may be readily displayed when desired.

The object of my invention is to provide a casing within which, by appropriate means, a large number of maps may be conveniently mounted and so arranged that any desired 15 map may be instantly drawn down and displayed; by which, in such case, it will be automatically held in position as long as desired, and when no longer wanted for use it may be rolled up and another displayed in like 20 manner if desired. Means is also provided by which any map or maps may be readily removed from the case for use independent thereof, each map being provided with individual spring roller mounting and hangers 25 ready for use, and the whole, while economical of construction, presents a neat and ornamental appearance.

The principles of my invention are illustrated in the drawings, in which—

30 Figure 1 is a front view of my device, the casing being partly removed; Fig. 2 represents an end view of the map cylinder looked at from the right; Fig. 3 represents a similar view in section of the other end of the map roller on the 35 line 3—3 of Fig. 1; Fig. 4 is a fractional portion of the end disk shown in Fig. 2, having the retaining lever shifted to disclose the map holding slot. Fig. 5 is an enlarged perspective view of one end of a map and its 40 holding frame as prepared for insertion in the device.

Further describing my invention with reference to the drawings, in which like characters of reference denote like parts throughout: 45 1 shows a frame work or casing within which the operative parts of my device are mounted to protect them from dust and the like.

50 2 is a disk preferably stamped from sheet metal of substantial thickness, having a series of radial grooves 2' corresponding in number to the number of maps to be mounted.

55 Pivoted at 3 are retaining levers 4 each provided with the notch 5. The pivotal attachment is such that the retaining lever will swing over the radial slot 2' and close the

same with the exception of such portions as correspond to the engaging notch 5. In closing the lever to its normal position it contacts with the clip 6 which is turned up from the edge of the radial slot 2' to form a suitable stop. The said retaining lever should be held in its thus described normal position by spring pressure, a means for which is shown in the leaf spring 7, secured to the lever at 8 by suitable notch therein. The other end of said spring bears upon a lug 9 which may be struck out from the material of the disk 2.

A depression or cup 10 may be pressed outwardly from the disk 2 to form a sort of hub within which may be seated the axial shaft 11. A disk 12 similar to 2 at the other end of the device is also provided with a similar hub into which the said shaft is seated and in 75 which, as in 10, it is securely attached by pins or screws 13. The said last named disk is also provided with circular openings 15 and a series of lugs 16 should be formed on the inner or facing side thereof, preferably by 80 punching them from the body of the disk and turning them up at right angles to the inner face thereof. Such projection or lugs should be equal in number to the openings 15 and equally spaced between them. The entire 85 frame work mounted on the central shaft 11 is journaled in the casing 1.

The several maps which are to be mounted in my device that illustrated being adapted to take eight, should be mounted on suitable 90 spring actuated rollers 18. Such rollers may be of the kind commonly used for window shades or maps, having a cylinder on which the map is rolled, and a spring contained therein having one end attached to the cylinder and the other to an axis journaled 95 therein. The fixed axis of said roller may be mounted on the clip 19, provided with a slot 20. Said clip, as shown in Fig. 5, is secured to the end of a bar 21. A similar clip at the 100 other end should also be supplied with a lug similar to that shown at 22. The bar and clips provide a supporting frame for each map and the whole structure should be so fixed that it will rest upon the central shaft 11. The lugs 16 provide means by which the rollers and frames are equally spaced about the map cylinder and held in rigid relation thereto. In placing one of the maps in my apparatus the lug 22 is inserted in one of the 110 openings 15 so that the supporting frame will rest on the central shaft 11 and contact

with those portions of the lugs 16 which face each other. The corresponding retaining lever at the other end is then moved to the position shown in Fig. 4, whereby the other 5 lug 22 at the other end of the map support may be carried through the radial groove 2' to the bottom thereof, whereby when said retaining lever is released it will be forced over by the spring 7 and, engaging the lug 22 10 within the notch 5, will securely retain and lock the map in position.

For convenience and ready changes each 15 map should be provided with its own frame work similar to that shown in Fig. 5. When it is desired to place such map in the apparatus or take one therefrom, for replacement the changes can readily and quickly be made as last above described.

I claim and desire to secure by Letters 20 Patent the following:

1. In combination with a map holder having a casing map carrying frames, lugs on each end of the map carrying frames, a revolvable cylinder journaled in said casing and 25 comprising a shaft, a disk at one end of the shaft provided with apertures to receive the lugs of one end of said frames, a disk at the other end of the shaft provided with radial slots and levers corresponding to each of said 30 slots pivoted to said disk so that their ends project therebeyond, and having notches through which the frame lugs on the opposite end of said frames are passed to be engaged by said levers, and lugs carried by the 35 first-mentioned disk to engage said frames at opposite sides thereof.

2. A map holder provided with map supporting frames, and projecting lugs carried by the ends of said frames, a disk having radial 40 slots to receive the lugs on one end of the frames, and levers projecting beyond the

disk pivoted thereto so as to swing over the slots and provided with notches whereby said levers are adapted to engage the frame lugs on one end of the frames when the levers 45 are swung over said slots, a second disk having apertures to receive the lugs on the opposite ends of said frames, and lugs struck out from the face of said second disk to engage with said frames. 50

3. In a map holder, a map supporting disk having a radial slot, a stop on one edge formed by turning up the material of said disk on one edge of the slot, a retaining arm pivoted to the disk, and means for normally 55 holding said lever in engagement with said stop.

4. In a map holder, the combination of a map cylinder therefor provided with an end disk having equidistant inwardly facing lugs 60 integrally formed thereon, of map frames and means for mutual engagement between the frames and the disk, each of said frames being adapted to be engaged by the lugs on each side thereof. 65

5. In a map holder, the combination of a map cylinder therefor having a central shaft and an end disk on said shaft having equidistant inwardly facing lugs integrally formed thereon, of map frames, and means 70 for mutual engagement between the frames and the disk, each of said frames being adapted to be engaged by the lugs on each side thereof, and to rest on said central shaft.

In witness whereof, I have hereunto set 75 my hand, this 22nd day of June A. D. 1907, in the presence of two subscribing witnesses.

ALBERT J. NYSTROM.
